SKIRT MARKER

Max Ingwer, Forest Hills, N. Y., assignor to Consolidated Sewing Machine & Supply Co. Inc., New York, N. Y., a corporation of New York

Application November 14, 1939, Serial No. 304,350

7 Claims. (Cl. 33—9)

The present invention relates to devices for marking skirt lengths.

Objects of the invention are to provide a simple, practical and inexpensive form of skirt marker, which can be quickly set to different heights from the floor and which will automatically hold to any position in which it may be set.

Further objects are to provide a device of the nature specified, which will consist of but few and simple parts, readily manufactured and easily assembled.

The foregoing and other desirable objects are attained by the novel features of construction, combinations and relations of parts hereinafter described, illustrated in the accompanying drawings and covered in the claims.

The drawings illustrate several of the different possible forms of the invention. Structure however may be further modified and changed all within the true intent and scope of the invention as hereinafter defined and claimed.

Fig. 1 is a broken part sectional view of one form of the complete device.

Fig. 2 is a sectional plan of the base as on line 2—2 of Fig. 1.

Fig. 3 is a broken side elevation of a modified form of base structure.

Fig. 4 is a plan view of the same, with the yardstick carried thereby indicated in section.

Fig. 5 is an enlarged broken part sectional side view of the powder holder.

Fig. 6 is a broken rear elevation of the same.

Fig. 7 is a plan view, with the pressure tube and supporting stick shown in section.

Fig. 8 is a broken side elevation of a modified form of powder container and spring holder for the same.

Fig. 9 is a broken horizontal sectional view as on the plane 9—9 of Fig. 8.

Fig. 10 is a broken part sectional side elevation of a modification in which the powder container is in the form of a jar detachably associated with the sliding, spring held nozzle head.

Fig. 11 is a plan view of the latter with the pressure tube and upright support indicated in section.

Fig. 12 is a broken sectional view of a duplex form of powder container.

Fig. 13 is a plan view of the same with parts broken and appearing in section.

In the general view, Fig. 1, an upright support is indicated at 15, on which is slidably mounted a powder containing box 16, having a discharge nozzle 17, and an air pressure connection 18.

The upright support 15, may be an ordinary

yardstick and it may be mounted in various ways in a suitable base. In Fig. 1, the base is a relatively heavy pin tray 19, having a socket 20, into which the end of the stick is slipped and in which it may be releasably secured by thumb screw 21, Fig. 2.

In Figs. 3 and 4, a folding type of base is shown, including strap metal parts 22, 23, pivotally connected one over the other at 24, and having downwardly angled ends 25, forming feet to rest on the floor. The top member 22, is shown as extended at one side and provided with a stick receiving opening 26, in line with a corresponding opening 27, in the inwardly turned extension 28, beneath the same. A thumb screw 21, releasably clamps the stick in these aligned seats in the top and bottom of the member 22. Fig. 3 shows how when this space is not in use, the lower or inner part 23, may be swung on pivot 24, into folded position in line with and beneath the upper part 22.

Pressure for expelling the marking powder through the nozzle 17, is provided in the present illustration by a hand bulb 29, connected by flexible tubing 30, with the pressure tube 18. The flexible tubing 30, is shown as run through a guide opening 31, near the upper end of the stick, so as to hold the bulb at a level where it can be readily reached in the various positions of vertical adjustment of the powder marker.

The powder holder is slidably confined to and yieldingly held on the upright by spring means consisting in the illustration of a single length of spring wire bent to form upper and lower spring arms 32, 33, engaging the back of the upright and connected by the side arms 34, having looped intermediate portions 35, hooked over the lugs 36, inset in the sides of the powder box. The upper and lower spring arms are shown covered by tubular elements forming rollers 37, the lower one of these covering and coupling the opposing end portions 38, of the single piece of the spring wire. The side portions 34, of the loop of spring wire are tensioned toward each other, so as to hold this loop engaged with the lugs or shoulders 36, on the opposite sides of the powder box.

To definitely guide the powder holder in sliding engagement with the stick, said holder is shown formed with an upright open groove 39, in the back of the same, said groove being of a size to freely receive the stick.

The pressure tubing may be a single continuous piece of metallic tubing, or part metallic tubing and flexible hose, or a single continuous length of

flexible hose. In the latter instance, the hose may be held by a grommet 40, Fig. 5, of resilient rubber, having an opening therethrough of a size to receive and yieldingly grip the rubber 5 hose 30, and having a peripheral groove at 41, engaged over a flange 42, of a screw ring 43, connected with the screw-threaded neck 44, on the top of the box. These parts are assembled by passing the end of the tubing through the grommet and then forcing the grommet into position over the flange of the screw cap or ring 43. The grommet is then confined in position frictionally gripping and holding the tubing and so held, the cap can be applied to or taken off the box whenever required, without loosening the tubing.

Figs. 8 and 9 illustrate a modified form in which shoulders for holding the retainer spring to the box are provided by simply forming upright grooves 45, in the opposite sides of the box 20 to receive substantially straight side portions 46, of the spring loop.

Figs. 10 and 11 illustrate a modification in which the powder holder is in two parts, an upper part 47, carrying the nozzle 17 and grooved at the 25 back at 39, and a lower part consisting of a jar 48, having a screw connection with the upper part at 49.

In Figs. 12 and 13, there is illustrated a modification in which there is an upper head portion 30 50, carrying the nozzle and the parts slidably held to and retained on the stick, a rotatably adjustable duplex compartment jar 51, seated in said head and a removable top 52, engaged over said jar. The head in this case is shown formed 35 as a circular ring 53, within which the jar seats on an annular flange 54, being retained in either one or the other of two diametrically reversed positions by notches in opposite edges engaging over corresponding ridges on said flange at 55. 40 In either of such reversible relations, a notch 56, in the upper edge of the compartment which is at the front, registers with the discharge nozzle 17. The cover 52, carries the pressure tubing 18, in position to open into the forward compartment. This cover is indicated as removably secured by bayonet joint connection at 57, and this cover is shown as engaging the partition 58, between the compartments in the closed position, so that pressure will be applied only to the powder 50 in the front compartment which is only in connection with the nozzle. With this form of the invention, powders of different color may be provided in the different compartments and used as best suited to mark different skirt materials.

55 What is claimed is:

1. A skirt marker comprising in combination, an upright support, a powder holder having a powder discharge outlet at the front of the same and having the back of the same slidably engaged with one side of said upright support, spring means slidably engaged with the opposite side of said support and yieldingly holding said powder holder in sliding engagement with said support and releasably retained in positions of 60 vertical adjustment on said upright support, a hand operated air pressure creating device connected with said powder holder, said spring means including spring arms bearing against said support at vertically separated points and substantially horizontally extending rollers on said 65 spring arms.

2. A skirt marker comprising in combination, an upright support, a powder holder having a powder discharge outlet at the front of the same and having the back of the same slidably en-

gaged with one side of said upright support, spring means slidably engaged with the opposite side of said support and yieldingly holding said powder holder in sliding engagement with said support and releasably retained in positions of 65 vertical adjustment on said upright support and a hand operated air pressure creating device connected with said powder holder, said holder being in two parts, an upper part carrying the powder discharge outlet and yieldingly and slidably engaged with the support and a lower multiple compartment part rotatably associated with said upper part and means for effecting selective connection of different compartments of said lower member with said air pressure creating device 15 and with said powder discharge outlet in different rotative positions of said lower member.

3. A skirt marker comprising an upright support, a powder container having the back of the same slidably engaged with the front of said support, said container having a powder discharge outlet in the front of the same, a loop of spring wire having spaced upper and lower portions slidably engaged with the back of said support and intermediate portions engaged with 20 said container to yieldingly hold said container slidably engaged with said support and retained in positions of vertical adjustment and hand operated air pressure creating means connected with said container, said loop being a 30 continuous length of wire with the ends of the same approached in opposing relation at the back of the support and a tubular retainer rotatably engaged over said approached wire ends and forming a roller engaging said support.

4. A skirt marker comprising an upright support, a powder container having one side slidably engaged with said support, a retaining spring yieldingly holding said container so engaged with said support and in positions of 40 vertical adjustment thereon, said container having a powder discharge outlet and hand operated air pressure creating means connected with said container, said retaining spring including a loop of spring wire engaged about portions of said 45 container and support and rollers on the portions engaging said support.

5. A skirt marker, comprising a powder ejector mounted for vertical adjustment and including a supporting ring having a powder discharge passage, a multiple compartment powder jar supported for angular adjustment in said ring and each compartment of the same having an outlet for registry with said powder discharge outlet, a cover for said angularly adjustable powder jar 55 removably engageable with said supporting ring and a pressure applying connection carried by said cover in position to register with the compartment which is in communication with said powder discharge outlet.

6. A skirt marker, comprising in combination, an upright support, a powder holder having a powder discharge outlet at the front of the same and having an open grooveway in the back of the same slidably engaged over the front of said upright support, spring means having upper and lower spring arms slidably engaged with the back of said upright support at vertically separated points and forwardly projecting intermediate side portions engaged with said powder holder at opposite sides of said open grooveway in the back of the holder and whereby said spring means is attached to said holder with the upper and lower spring arms bearing against the back of the upright support to hold the back of the 75

powder holder slidingly engaged over the front of said upright support and hand operated air pressure creating means connected with said powder holder.

- 5 7. A skirt marker, comprising in combination, an upright support, a powder holder including an upper part having a powder discharge outlet in the front of the same and an open grooveway in the back of the same and a lower powder containing part detachably connected to the underside of said upper part, said upper part of the powder holder being disposed with the open
- 10 grooveway in the back of the same slidingly engaged over the front of said upright support, air supply tubing extending down through the top of said upper part into said lower powder containing part of said powder holder and spring means including vertically spaced upper and lower spring arms slidingly engaging the back of the upright support and forwardly projecting intermediate side arms connected with said upper holder part at opposite sides of said open groove- 10 way.

MAX INGWER.
